PLIERS AND THE LIKE

Filed Dec. 9, 1929

FIG. 1.

FIG. 2.

INVENTOR:
Edward H. Wigand
BY David E. Carlson
ATTORNEY.

UNITED STATES PATENT OFFICE

EDWARD H. WIGAND, OF ST. PAUL, MINNESOTA

PLIERS AND THE LIKE

Application filed December 9, 1929. Serial No. 412,786.

My invention relates to improvements in lower end on a pivot pin or bolt 14 within wrenches, pliers and like implements such as used by mechanics in general, the main object of the invention being to provide a wrench with increased scope of utility, including means for increasing leverage available as compared to two-piece levers and consequently create an increased gripping condition on objects such as bolt heads, shafts, piping and other articles.

With the above main objects in view the invention consists of improvements herein fully set forth and illustrated in the accompanying drawings, in which,—

15 Fig. 1 is a top edge view of my improved pliers or wrench-pliers, in a preferred form.

Fig. 2 is a side elevation of Fig. 1 with a part of one jaw member partly in section, the pliers being shown closed, in full lines, 20 and in dotted lines one jaw and handle member shown dotted with the jaws engaging a round pipe-like object.

Referring to the drawings by reference numerals, I have for illustrative purpose 25 only, shown my device as embodied in a pair of pipe-pliers, the tool having the usual jaw members 5—5A shown serrated interiorly, said jaws being pivoted and crossed at 7. The upper jaw has an integral handle or 30 lever 8 while the lower jaw 5 has an integral lever arm 9 comparatively short and extending rearwardly and upwardly from the pivot 7 in spaced relation to and above lever 8. 10 are a pair of transversely spaced, 35 parallel ears, on lever 8 rearward of pivot 7 and in which is pivoted on a pin 11 the front end of an upper hand lever 12 which is a counterpart of that part of lever 8 rearward of pivot 11. The levers 8—12 are 40 gripped simultaneously to close the jaws 5A—5, there being provided adjustable connecting means between lever 12 and the adjacent jaw arm 9 above it as will presently be described.

45 13 is an upright rack-bar pivoted at its

a slot 15 of lever 12, said pin being insertable through said rack-bar and any pair of a number of pairs of holes 16. Above pivot 14 the rear edge of the bar comprises a 50 toothed-rack normally extending through and above a longitudinal slot 17 of jaw-lever 9. In the forward part of said slot is an integral tooth 17T which is engaged by any of the teeth of the rack bar, said bar 55 being impelled rearwardly into contact with said tooth 17T by a flat-spring 18 bearing yieldingly against the forward edge of the rack bar (see Fig. 2).

For ordinary wrench purposes the device 60 may be set as shown in full lines in Fig. 2, that is with the jaw member 5A—5 contacting with each other when the lever members 8—12 are nearly closed. Assuming that the jaws are desired to be engaged with maximum grip as on a pipe, designated 19 in Fig. 2, the arm 9 is moved upwardly, the bar 13 first being pressed forward until tooth 17T engages one of the upper teeth of the rack bar and lever 12 may also be 70 moved away from lever 8 as to dotted position in Fig. 2. This variable adjustment is readily made with one hand if the operator first sets the lever 9 to a wide angle, so that the outermost tooth of rack bar 13 is engaged, the jaws 5A—5 being then considerably spread. When the jaws are then placed to straddle an object, as 19, the operator presses down on the rear end of lever 9 with the thumb of the hand which grips the levers 8—12 until the object 19 is loosely engaged, the corresponding tooth of rack 75 13 then being engaged by tooth 17T. Then to move or turn an object 19 the jaws 5A—5 are clamped tight to it when the operator 80 clamps the levers 12—8 tightly pulling on rack 13 which in turn pulls jaw arm 9 toward lever 8 with considerable force.

The leverage available and increase of leverage is of course directly governed by the 85

- relative lengths of so-called power-arm or leverage in bar 12 between its fulcrum 11 and pin 14 and the lever arm in member 9 between its tooth 17T and its fulcrum 7. 5 The lever-arm in member 12 is of course variable according to which pair of holes 16 the fulcrum pin 14 of bar 13 is engaged in. A feature of this wrench is the last described operation in which the jaws 5A—5 are spread apart initially and then closed, to contact with an object to be held, by a simple pressure movement on the rear part of arm 9 by the thumb of the same hand which grasps the levers 12—8. 10 It will now be readily understood that this device in itself is a powerful wrench if made in about the proportions shown, but is further efficient and more powerful if the levers 8—12 are longer, other parts remaining the same. The levers 8—12 may be extended either by making them long or by putting a pipe on either or both of them providing ample leverage for heavy work. 15 As an example of the versatility of these pliers it will be readily understood that the levers 12—8 can be made straight and of considerable length, the jaws spread as desired and the entire device used as a handling means for red-hot irons in forge or blacksmith shops or such elongated device used for removing clinkers from a furnace fire-pot, or grasping nuts or bolts in machines of various kinds where such nuts and bolts are otherwise almost inaccessible. 20 The invention disclosed may also be embodied in tinsmith's snips or sheet metal cutters in general and it is obvious that in a pair of snips for cutting sheet metal powerful leverage is available up to the very tips 25 of the cutting jaws of such implement. 30 35 40 45 50 55 60 65 70 75 80 85 90 95 100 105 110 115 120 125 130
- I claim:
1. A pair of pliers comprising two counterpart jaw members crossed and pivotally connected, a main lever arm extending integrally from one of said jaw members and comprising one member of two hand operated levers, a secondary hand operated lever extending in a common plane with the said first lever rearwardly of the jaws and the forward end thereof fulcrumed rearwardly of the jaw-fulcrum; the other of said jaw members comprising in part an integral short arm extending rearwardly from its fulcrum and in proximity to the forward part and outwardly of the secondary hand lever described, a toothed rack bar pivoted to said short hand lever rearward of its fulcrum and adjustably engaging the said short jaw arm and yieldable means pressing said bar into engagement with said arm. 2. The structure specified in claim 1 in which said short-arm is slotted longitudinally near its rear end, said rack bar means comprising a toothed bar pivotally fixed in the second hand lever in variable positions rela-

tive to the fulcrum of the latter lever and said bar projecting through said slot and normally pressed into engagement with the metal of said short jaw-arm in the rear part of said slot, and a spring fixed on said jaw-arm and contacting with said rack bar to continuously but yieldingly press said rack bar into contact with the jaw-arm for the purpose set forth.

In testimony whereof I affix my signature. 75
EDWARD H. WIGAND.
